UNITED STATES PATENT OFFICE.

THOMAS J. O'BRIEN, OF CAIRO, ILLINOIS.

CLUTCH-PULLEY.

SPECIFICATION forming part of Letters Patent No. 634,367, dated October 3, 1899.

Application filed October 22, 1898. Serial No. 694,264. (No model.)

To all whom it may concern:

Be it known that I, THOMAS J. O'BRIEN, of Cairo, in the county of Alexander and State of Illinois, have invented a new and Improved 5 Clutch-Pulley, of which the following is a full, clear, and exact description.

This invention relates to improvements in friction clutch-pulleys for belting, and the object is to provide a pulley of this class which 10 shall be comparatively simple in its construction and therefore not liable to get out of order, that will have an equal friction-pressure on both sides, and in which the strain of the belt will be directly in the center.

15 I will describe a clutch-pulley embodying my invention and then point out the novel features in the appended claim.

Reference is to be had to the accompanying drawings, forming a part of this specification, 20 in which similar characters of reference indicate corresponding parts in both views.

Figure 1 is a section through the line 1 1 of Fig. 2 of a clutch-pulley embodying my invention, and Fig. 2 is a section on the line 2 2 25 of Fig. 1.

The pulley comprises two side pieces or webs 1 2, which may be in the form of spoke-wheels or in the form of solid disks. Each side portion or web has a hub 3, which loosely 30 engages on the driving-shaft 4, and to the periphery of these webs the pulley-rim 5 is attached by means of bolts 6. Rigidly attached to the shaft 4, between the side pieces or webs 1 2, is a friction-disk 7, having annular projections 8 9 near its periphery. These 35 projections are here shown as V-shaped in cross-section, but obviously they may be otherwise shaped without departing from the spirit of my invention.

40 Attached to the inner surface of the side piece or web 2 is a bearing-ring 10, which may consist of wood. This bearing-ring 10 has an annular channel on its inner side within which the projection 9 of the friction-disk is de- 45 signed to engage. Mounted to slide relatively to the side portion or web 1 is a bearing-ring 11, also of wood and having on its inner side an annular channel to receive the projection 8 of the friction-disk. From the bearing-ring 50 11 stems 12 extend outward through openings in the side piece or web 1 and have piv-

otal connection at their outer ends with angle-levers 13, pivoted between lugs 14, formed on the hub 3 of the side piece or web 1. From the centrally-disposed members of these angle-levers links 15 extend and have pivotal connection with a sleeve 16, loosely mounted on the shaft 4. This sleeve is made quite long, so as to have a considerable bearing on the shaft, and preferably it will be made in two sections, as indicated, so that it may be readily placed on the shaft.

Seated in an annular channel formed in the sleeve 16 is a shifting-ring 17, with which the ordinary shifting-lever is designed to engage. 65 Springs 18 are seated in recesses formed in the hub of the friction-disk 7 and bear at their outer ends against the side portions or webs, for a purpose which will hereinafter appear. When the parts are in the position indicated in Fig. 1, the disk 7 will of course 70 rotate with the shaft 4 and the pulley will remain stationary, as will also the sleeve 16 and its connections with the pulley. When it is desired that the pulley shall be rotated, the 75 sleeve 16 is to be moved toward the pulley by means of its shifting-lever, and this movement of the sleeve will rock the angle-lever 13, which will force the bearing-ring 11 into close engagement with the friction-disk, and 80 a slightly farther inward movement of the sleeve will cause the pulley to be moved in such direction as to engage the friction-ring 10 with the projection 9 of the friction-disk. When the sleeve 16 is moved in the opposite 85 direction, the springs 18 will move the pulley to its loose or stationary position.

As the friction-disk is arranged in the center of the pulley it is evident that the strain of the belt will be equally distributed across 90 the pulley.

Having thus described my invention, I claim as new and desire to secure by Letters Patent—

A clutch-pulley, comprising side pieces 95 loosely mounted on a shaft, a rim rigidly secured to both of the side pieces, a friction-disk rigidly secured to the shaft between the side pieces and within the pulley-rim, a bearing-ring attached to the inner side of one of 100 the side pieces and adapted for engagement with the disk, a bearing-ring movable on the

inner side of the other side piece and adapted to engage with the disk, stems extended outward from the movable ring, angle-levers having pivotal connection with said stems and also with the side piece through which the stems extend, a sleeve loosely mounted on the shaft and in which the shaft may ro-

tate, and link connections between said sleeve and the angle-levers, substantially as specified.

THOMAS J. O'BRIEN.
